UNITED STATES PATENT OFFICE.

RUDOLPH W. MENK, OF JOLIET, ILLINOIS, ASSIGNOR TO THE EXCELSIOR STEEL FURNACE COMPANY, OF CHICAGO, ILLINOIS, A CORPORATION OF ILLINOIS.

AIR CIRCULATOR AND HUMIDIFIER FOR FURNACES AND HEATERS.

1,365,842.

Specification of Letters Patent. Patented Jan. 18, 1921.

Application filed March 8, 1920. Serial No. 363,962.

To all whom it may concern:

Be it known that I, RUDOLPH W. MENK, a citizen of the United States, residing at Joliet, in the county of Will and State of Illinois, have invented a new and useful Improvement in Air Circulators and Humidifiers for Furnaces and Heaters, of which the following is a specification.

My invention relates to apparatus or means for increasing the velocity of air circulated around the fire-pot and around and through the radiator of a hot-air heater or furnace, and in this connection I provide means that are adapted to humidify the air during its circulation.

Among the divers objects of my present invention are the provision of means that are adapted to draw out a portion of the cool air supply in the usual return flues or air supply of a warm air furnace or heater and to increase the velocity thereof by means of a turbine or fan that discharges the drawn out air into the furnace shell between the latter and the heating element. Another object is to provide means for discharging a quantity of sprayed or atomized fluid into the air return flue during the operation of the device. Another object of this invention is the provision of a circulating and humidifying structure that is adapted to be installed in a furnace already in use, without having to alter the construction thereof. And still further objects are the provisions of a structure that is simple in arrangement, economical to manufacture, relatively easy to assemble, and effective in its operation. These objects I prefer to attain substantially in the manner hereinafter pointed out. Reference will now be made to the accompanying drawings that form a part of this specification, in which—

Figure 1 is a perspective view of the rear of a warm air heater or furnace showing my improvements installed thereon, and portions of the furnace being broken away for clearness.

Fig. 2 is a horizontal plan of my apparatus, the furnace and heating unit being in section on line 2—2 of Fig. 1.

Fig. 3 is a side elevation of my device.

Fig. 4 is a rear view thereof.

Fig. 5 is a transverse vertical section of the discharge nozzle, detached.

Referring more particularly to Fig. 1, the furnace, preferably, comprises the usual metal outer shell 10, surrounding and spaced from the cast iron heating element 11 of any of the usual or well known types to provide an air heating chamber therebetween. The cold air from the apartments being heated is drawn down through oppositely arranged cold air flues 12, to a box-like structure 13, which is disposed with its bottom adjacent the floor and communicates with the lower portion of the chamber between the exterior shell and the heating element of the furnace where the cool air becomes heated and circulates about the heating element and is discharged from the drum or shell through suitable outlets 14 in the top or upper portion of the shell. The structure thus far described is a typical warm air furnace or heater and forms no essential portion of my invention.

Mounted, preferably, at the rear of the furnace and spaced away from shell 10, is a blower 15 of any suitable type that is driven by a motor 16 preferably mounted upon one side of the casing thereof. From the exhaust outlet of the blower, I provide a conduit 17 leading through shell 10 of the furnace structure where the same connects with the neck or throat portion 18 of a crescent shape or annular discharging device 19 that extends around the lower portion of the heating element of the furnace between the heating element and the shell and spaced from each of these parts a slight distance. This discharging device 19 is, preferably, of triangular shape in cross-section and extends from near one of the walls of the ash-pit opening around the heating element to the opposite ashpit wall, while its upper portion is provided with a concentric discharge opening 20 through which the air driven into the structure by blower 15 is discharged in an upward direction, thereby assisting in the circulation of the air received into the furnace shell through the cool air pipe 12, herefore mentioned.

In order to further assist in increasing the velocity of the air, I prefer to connect

the inlet portions of the blower to a suitable conduit 21 that extends laterally out from the blower and has one extension 22 that leads to and through box 13 upon one side 5 of the furnace, and a branch 23 that leads to and through box 13 upon the opposite side of the furnace. The ends of these branches 22 and 23 terminate in upturned stubs 24 and 25, respectively, that extend up into 10 the cool air conduit 12 a short distance, as seen in Figs. 1, 3 and 4 of the drawings. Thus, it will be seen that the air being drawn to the inlet of the blower is taken out of the cool air conduits 12 and thereby acts 15 kinetically or through friction to increase the velocity of the downwardly moving current of air therein, and this air upon leaving the blower is materially increased in its velocity and blown into the semi-circular dis- 20 charging device 19 within the heating chamber of the furnace where its upward direction materially assists in increasing the velocity of the air reaching the heating chamber from the usual cool air conduits and in- 25 creasing the velocity thereof for a better circulation. It will also be seen that the inter- position of the blower, and its inlet and ex- 30 haust conduits, acts as a "booster" for the cool air at two points in the cycle of the circulation of the cool air to and in the heating chamber.

I have provided suitable means, as before stated, for humidifying the air in its transit to the heating chamber, which preferably comprises a small pump 26 the shaft whereof is positioned substantially in alinement with the shaft of motor 16, and I connect these parts by a shaft 27 so that when the motor is operating to drive the blower it will at the same time actuate pump 26. Positioned either in or below the box-like structures 13, and preferably, below the adjacent portions of conduits 22 and 23, are pans 28 and 29 that contain a quantity 45 of water or other suitable fluid, and are provided with outlet pipes 30 and 31, respectively, that lead therefrom to a T or union 32, and are connected therefrom to the pump by the inlet pipe 33 of said pump. 50 The outlet pipe 34, leading from the discharge end of the pump, is connected to a T or union 35 that has discharge pipes 36 and 37 leading in opposite directions therefrom, the ends of which pipes 36 and 37, extend 55 into and terminate within the box-like structure 13 of the furnace in planes above the respective conduits 22 and 23. These conduits and the respective pipes 36 and 37 within the box-like structure 13 are also 60 in a vertical plane above and in alinement with water pans 28 and 29, and said pipes 36 and 37 are each provided within the box-like structure 13, with discharge orifices that permit the water pumped into pipes 36 and 37 to be sprayed or discharged in fine

streams in the box-like structure and in a downward direction toward and into pans 28 and 29, which act as reservoirs and permit the return of the unevaporated water to the pump. This spraying of the water 70 takes place in the path of the cool air that is moving toward the heating chamber of the furnace and materially moistens or humidifies this air so that it becomes revitalized and in a better condition for heating 75 and discharging into the apartment to be heated.

From the foregoing, it will be obvious that I have provided a means for increasing the velocity of the air leading to the furnace 80 by providing a suction in the cool air conduits and by discharging the air from the blower in a jet inside the heating compartment the velocity of the upwardly rising warm air is materially increased, and at the 85 same time means are provided whereby the air is moistened or humidified in its transit to the heating chamber. It will also be ob- 90 vious to others that divers arrangements of this structure may be provided without ma- 95 terially departing from the disclosure herein made, and I, therefore, desire it under- stood that such changes are contemplated within the scope of the appended claims.

What I claim as new is:—

1. The combination with a furnace having a heating element, a shell inclosing the same and spaced therefrom to provide a heating chamber, and a cool air conduit commun- 100 icating with and discharging into said heat- ing chamber, of a blower, an inlet conduit lead- 105 ing from said cool air conduit to said blower, a discharge conduit leading from said blower and terminating in said heating chamber, and means connected to said discharge conduit and positioned within said heating chamber, whereby the air dis- charged through said means is directed and circu- 110 lated around the heating element of the furnace.

2. The combination with a furnace hav- 115 ing a heating element, a shell inclosing the same and spaced therefrom to provide a heating chamber, and a cool air conduit commun- 120 icating with and discharging into said heat- ing chamber, of a blower, an inlet conduit lead- 125 ing from said cool air conduit to said blower, and a discharge conduit leading from said blower and terminating in said heating chamber, and arranged con- centrically around the heating element, where- 130 by the air discharged through the same is directed and circulated around the heating element of the furnace.

3. The combination with a furnace hav- 125 ing a heating element, a shell inclosing the same and spaced therefrom to provide a heating chamber, and a cool air conduit commun- 130 icating with and discharging into said heating chamber, of a blower, an inlet

conduit leading from said cool air conduit to said blower, a discharge conduit leading from said blower and terminating in said heating chamber, and a segmental shaped discharging device surrounding and concentric with a portion of the heating element and having an opening in its upper portion, whereby the air discharged from said device is directed and circulated substantially entirely around said heating element and the air so discharged is given an upward direction of flow.

cating through the lower portion of said shell with said heating chamber, of a blower, an inlet conduit leading from said cool air conduit to said blower, a discharge conduit leading from said blower and terminating in said heating chamber, a discharging device connected to said discharge conduit and positioned within said heating chamber, whereby the air discharged through said discharging device is circulated around the heating element of the furnace, and means for spraying water into said cool air conduit.

said discharging device is circulated around the heating element of the furnace, a fluid receptacle in the lower portion of said cool air conduit, a pump, a pipe leading from said receptacle to said pump, a separate pipe leading from said pump to said cool air conduit and discharging therein in a plane above the plane of said receptacle, a

motor actuating said blower, and a shaft connecting said motor and pump.

Signed at Chicago, county of Cook and State of Illinois, this 23rd day of February, 1920.

RUDOLPH W. MENK.

Witness:

E. K. LUNDY, Jr.
